CLOCK CASING

Donald E. Protzmann, Litchfield, Conn., assignor to
General Time Corporation, Stamford, Conn., a
corporation of Delaware

Filed May 14, 1968, Ser. No. 11,931

Term of patent 14 years

Int. Cl. D10—01

U.S. Cl. D42—7

FIG. 1 is a perspective view of a clock casing showing my new design, the surface shading indicating a material having the appearance of wood;

FIG. 2 is a left side elevational view; and

FIG. 3 is a top plan view.

The broken line showing of a clock face and hands in FIG. 1 is for illustrative purposes only. The rear (not shown) is plain and unornamented.

I claim:

The ornamental design for a clock casing, substantially as shown and described.
